UNITED STATES PATENT OFFICE

RUDOLPH H. JOHNSON, OF CHICAGO, ILLINOIS

METHOD AND MEANS FOR UTILIZING THERMIONIC TUBES HAVING OPEN FILAMENTS

Application filed June 18, 1928. Serial No. 286,089.

My invention relates to methods and means for utilizing thermionic tubes having open filaments, its general object being the provision of a comparatively simple and inexpensive device which will permit the continued use of thermionic tubes after the filaments thereof have been burned out, or otherwise destroyed.

Another object of my invention is to effect a substantial saving in the equipment required for charging storage batteries by making use of burnt out bulbs, hitherto considered as valueless for rectifying purposes.

Other objects and advantages of the invention will appear more fully in the hereinafter specification when taken in connection with the accompanying drawing, in which

Figure 1 is a diagrammatic view of a circuit showing a rectifying bulb with its glass envelope partly in section and partly broken away, incorporated therein;

Figure 2 is a diagrammatic view of a modified form of a circuit showing a rectifying bulb in perspective embodied therein.

Figure 3 is a diagrammatic view of another modified method and means for accomplishing the object of my invention.

In the drawing, wherein similar characters of reference indicate corresponding parts in the views, 4 designates the primary of a transformer, A—the terminals 5 and 6 of which are connected to an alternating current source of potential. B designates the secondary of the transformer, the secondary being tapped at the point 7 in order to provide a source of comparatively low potential for charging purposes, as will hereinafter appear.

Referring to Figure 1, the circuit 8 includes a switch 9, a spark-gap 10, the rectifying bulb 11 and the storage battery 12. It will be observed that when the primary 4 of the transformer A is energized, a current of high potential will traverse the circuit 8 when the switch 9 is closed, the current bridging the gap between the cathode 13 and the anode 14. The cathode in the present case may be either half of the open filament 13' and its attached supporting rod connected to the base 11'. The condenser 15, as is usual

in these circuits, merely serves to facilitate the building up of potentials suitable for passing over the spark-gap 10 and the space between the electrodes 13 and 14 within the rectifying bulb. It is to be observed that after the current has been flashed across the electrodes 13 and 14 in the tube, the switch 9 may be opened, leaving the secondary circuit to be completed through the right hand wing 16 of the secondary B, the potential in this wing being suitable for ordinary battery charging. The lead from the tapping 7 extends to a point between the spark gap 10 and rectifying bulb 11 so as to provide a current of low potential utilizing only the right hand wing 16 when the main circuit including the switch 9 is open. To facilitate this operation, the lead from the tapping 7 is provided with a switch 7' which is opened when a current of high potential is established by closing switch 9, but which is closed to maintain a current of low potential when switch 9 is open.

In Figure 2, 17 designates the primary of the transformer, one terminal 18 of which is suitably connected to a conventional switch 19, the other terminal 20 of the primary leading to a source of alternating current. When the switch 19 is closed, an alternating current will flow in the primary 17 thereby inducing a high voltage secondary current to flow in the secondary circuit 21 which includes the condenser 22, the spark-gap 23 and the rectifying bulb 24. Prior to the closing of the switch 19, the customary potential in the alternating current mains will be insufficient to pass current through the primary circuit which includes the battery 27, the electrodes 25 and 26 of the rectifying bulb 24, and the return lead 28 to the mains. However, when the switch 19 is closed the induced high potential will immediately pass current across the spark-gap 23 and the electrodes 25 and 26, after which the low potential current will flow through the tube 25 in the usual manner, when the switch 19 is thrown open, thereby eliminating current from the secondary circuit 21. If desired, conventional relays may be employed instead of the switches 9 and 19, the relays serving 100

to automatically cut out the high potential circuit when low potential current begins to pass through the bulb.

Heretofore, after a period equivalent to about one thousand hours of use, the filament of the average rectifying bulb of the type indicated is either burned out or has become fragile to a point where its fracture has occurred. As is well known, rectifying bulbs of the type indicated, especially the larger size, are expensive and their frequent replacement in commercial establishments involves a considerable financial outlay. Following the usual practice, upon the burning out or fracture of the filament, the bulbs were discarded. By the method and means herein indicated, it is to be noted that these rectifying bulbs may be now reemployed, even after the filaments have been fractured, as illustrated. The life of these tubes may now be prolonged to a point dependent only upon the current conducting properties of the gas within the glass envelope. The rectifying results obtained are approximately equal in most cases to those obtained by the bulb prior to the destruction of the filament. In actual practice, the transformer circuits illustrated in Figures 1 and 2 are incorporated within a compact box or casing, these being supplied with a convenient handle for carrying about.

In Figure 3,—29, 30, designate the primary and secondary windings, respectively, of a step-down transformer, the winding 30 of which I connect to the primary 31 of a conventional spark coil transformer D, one of the terminals 33 of the secondary 32 of the latter being led to the open filament 34, the other secondary being connected through a spark gap 35 to the anode 36 of the rectifying bulb 37. On inspection of Figure 3 it will now be observed that when the terminals 29' of the primary of the step-down transformer are energized by alternating current from the mains, current will be supplied the spark coil transformer D, causing a high potential current to flash across spark gap 35 and to bridge the space between the anode and filament of the bulb 37, thereby breaking down the initial resistance offered to the passage of a current between the electrodes of the bulb, whereupon the circuit 38 wired in parallel with the primary 29, and including the battery 39, will now permit alternating current direct from the mains to pass between the electrodes of the bulb 37 for the purpose of charging the battery in the usual manner.

I am aware of rectifying thermionic bulbs, particularly of the gaseous type, which do not employ filaments, but the method I now employ for the continued use of rectifying bulbs having open filaments, I believe to be original in the related industry.

It will be obvious to those skilled in the art to which my invention appertains, that

modification and change may be made in the circuits and instrumentalities employed for the achievement of the objects I have indicated; hence I do not confine myself to the details precisely as set forth only in so far as they are circumscribed by the appended claims.

What I claim is new and desire to secure by Letters Patent:

1. A rectifying circuit of the character described, comprising a transformer having a primary directly connected to an alternating current supply and a secondary tapped to provide two branch secondary circuits, the first of said secondary branch circuits provided with separated electrodes to establish a spark gap, a rectifying tube connected in the main circuit including said second secondary branch circuit, said rectifying tube requiring a higher initial energizing potential than normally induced in said second branch secondary circuit, a lead from the tapping between said secondary portions to the main circuit, a switch in said first secondary branch circuit between said secondary and said lead connection for establishing a current of high potential, a switch in said lead adapted to be closed to maintain a current of low potential when said first mentioned switch is open, and a rectified current receiving device connected in series with said rectifying tube in said second secondary branch circuit.

2. A rectifying circuit of the character described, comprising a transformer having a primary directly connected to an alternating current supply and a secondary tapped to provide two branch secondary circuits, the first of said secondary branch circuits provided with separated electrodes to establish a spark gap, a rectifying tube connected in the main circuit including said second secondary branch circuit, said rectifying tube requiring a higher initial energizing potential than normally induced in said second branch secondary circuit, a lead from the tapping between said secondary portions to the main circuit, a switch in said first secondary branch circuit between said secondary and said lead connection for establishing a current of high potential, a switch in said lead adapted to be closed to maintain a current of low potential when said first mentioned switch is open, a rectified current receiving device connected in series with said rectifying tube in said second secondary branch circuit, and a condenser shunted across the conductors leading to said rectifying tube and rectified current receiving device.

In testimony whereof I have signed my name to this specification.

RUDOLPH H. JOHNSON.
